UNITED STATES PATENT OFFICE.

HENRY M. LOOMER, OF BEVERLY, MASSACHUSETTS, ASSIGNOR TO UNITED SHOE MACHINERY CORPORATION, OF PATERSON, NEW JERSEY, A CORPORATION OF NEW JERSEY.

GRINDING-MACHINE FOR ROTARY CUTTERS.

1,386,638.

Specification of Letters Patent.

Patented Aug. 9, 1921.

Application filed October 20, 1919. Serial No. 331,887.

To all whom it may concern:

Be it known that I, HENRY M. LOOMER, a citizen of the United States, residing at Beverly, in the county of Essex and State 5 of Massachusetts, have invented certain Improvements in Grinding-Machines for Rotary Cutters, of which the following description, in connection with the accompanying drawings, is a specification, like referring 10 to characters on the drawings indicating like parts in the several figures.

This invention relates to mechanism for grinding rotary cutters such, for example, as are used for trimming the edges of the 15 reparts of boot and shoe soles.

Various mechanisms have been devised for grinding cutters of the type shown in the patent to Loomer 1,105,672 wherein the front face of each tooth is located at a 20 predetermined angle with respect to the axis of the cutter. The diameters of cutters vary and the axial lengths thereof also vary according to the character of the work to be performed by the cutters. Different shapes 25 and sizes of cutters vary considerably in the angle between the plane of the cutting face and the plane of the end face of the cutters.

In a former application filed by me April 30 17, 1917, Serial No. 162,758 I have described and illustrated a grinding mechanism capable of accurately locating the cutter with respect to the grinding member and controlling the position of the cutter to effect proper 35 grinding of the teeth; the mechanism of that device including a longitudinally extensible arm which is pivotally mounted on a support and carries the cutter in such direction relatively to the grinding wheel that said 40 cutter moves in the arc of a circle parallel with the plane of the grinding wheel, the arm being manipulated by the operator so that the cutter sweeps past the grinding wheel in said arc.

An important object of the present invention 45 is to provide an improved grinding device of the character described which will be so organized as to insure that the proper angle of the work relatively to the grinding 50 wheel will be maintained regardless of changes which may be effected in the length of the arm carrying the cutter.

In factories which use grinding machines of this general character, it is customary to also use other machines or devices which are 55 frequently moved from place to place. For instance, shoe racks mounted on casters are, for convenience, rolled up close to the edge cutting machines near which it is customary and convenient to locate the cutter grinding 60 machine. If such a shoe rack or other movable appliance contacts with the cutter supporting attachment there is liability of injuring the attachment or disarranging the relative adjustment of the parts thereof. To 65 avoid risk of this, it is desirable to remove the attachment when not in use. To enable the attachment to be easily removed as a whole and replaced as a whole without disturbing the relatively adjusted position of 70 the parts thereof, and with practical certainty that the cutter support or table will occupy the same position when returned after removal that it occupied before removal, is another object of the present in- 75 vention.

Accordingly, a further feature of the invention consists in a grinding machine having a removable work-supporting attachment, and means for adjustably determining 80 the position of the attachment relatively to the grinding member of the machine to enable the attachment, after removal, to be replaced so as to present the work to the grinder in a relationship determined by its 85 setting prior to removal. Preferably, and in accordance with a further feature of the invention the machine frame and the attachment are provided with coöperating members, one of which is adjustable, to determine 90 the relative positions of the grinder and attachment.

Further features of the invention relate to the arrangement of the cutter supporting device whereby the cutter may be oscillated from a position out of contact with the grinding wheel into contact therewith and beyond to a variable point which may be predetermined by adjustment. 95

The invention will be more readily understood from the following specification taken in connection with the accompanying drawings in which,

Figure 1 is a perspective view of a grind-

ing member and my improved cutter supporting device in one of its embodiments;

Fig. 2 represents a section on line 2—2 of Fig. 1 looking toward the grinding member;

5 Fig. 3 is a plan view of the parts shown at the left of Fig. 1;

Fig. 4 is a perspective view, partly broken out, illustrating another embodiment of the invention;

10 Fig. 5 represents a section on line 5—5 of Fig. 4; and

Fig. 6 is a plan view of a portion of the device shown in Fig. 4.

A portion of the frame of the machine is indicated at 12, the same having bearings 13 for a shaft 14 carrying the disk-shaped grinding member 15, the shaft being driven by any suitable means such as a belt applied to the pulley 16.

20 Fig. 17 for carrying the support to which the cutter carrying arm is resiliently pivoted as hereinafter described is provided with a slot 18 at its inner end. A wing nut 19 applied to a screw 20 rising from a ledge 25 21 of the frame, enables the bracket 17, after it has been adjusted as hereinafter described, to be clamped in operative relationship to the frame and grinding member.

The outer end of the bracket 17 has a 30 transverse slot 22 through which a screw 23 passes into the base or slide 24 of the support to which the cutter carrying arm is pivotally connected. A groove 25 in the under side of the base 24 fits a rib 26 of the 35 bracket 17. The said bracket is formed or provided with slots forming rack teeth 27 engaged by a pinion 28 carried by a shaft 29 having a handle 30 and mounted in the slideable base 24. By loosening the screw 23 and 40 then rotating the shaft 29, the base or slide 24 can be adjusted in a direction substantially parallel with the axis of rotation of the grinding wheel, the rib and groove 26, 25, guiding the slide in such movement.

45 After the adjustment is effected a tightening of the screw 23 which carries a suitable washer as indicated by dotted lines in Fig. 1 securely holds the slide 24 in its adjusted position.

50 The slide 24 has ears 31 in which is mounted a pin 32, said pin also passing into or through ears 33 of a bar 34, the pin 32 therefore providing a pivot for the bar 34 and the arm 35 which projects therefrom, preferably integral therewith. A spring 36 carried around the pin 32 acts, as hereinafter described, to normally hold the arm 35 swung upwardly.

The arm 35 has a longitudinal groove 37 60 preferably somewhat V-shaped as shown in Fig. 2, the outer end of the arm being enlarged as at 38. The shank 39 of the cutter support or table 40 having a pin 41, is mounted in the groove 37 of arm 35 and secured therein by an eye bolt 42 having a

threaded end 43 which is engaged by a wing nut 44. This eye bolt is employed to clamp the shank 39 of the cutter support 40 after the same has been adjusted longitudinally of the arm 35 and rotatively therein.

70 When it is desired to vary the angular adjustment of the pin 41 on which the cutter C is mounted, or to alter the longitudinal position of the shank 39 relatively to the arm 35, the wing nut 44 is loosened, the adjustment effected, and the wing nut 44 is again set up. In order that the angular adjustment of the table 40 and its pin 41 may be determined, and maintained during any relative movements while the nut 44 is loosened, I provide means for preventing any disturbance of that angular adjustment. Said means, in the embodiment of the invention illustrated in Figs. 1 and 2, comprises a lug 45 projecting laterally from the arm 39, 80 a stop screw 46 passing through said lug and having a binding nut 47, these parts being so formed that the lower end of the screw 46 is adapted to bear upon the flat level surface of the arm 35 at one side of its groove 37. 90

It will now be understood that after having once determined the proper angular adjustment for the table 40 and its pin 41 and after once clamping the eye bolt 42, the screw 46 will be adjusted so that its lower end will bear upon the surface of the arm 35 just described. Afterward, if there is any occasion for loosening the eye bolt, either to enable the shank 39 to be shifted along the arm 35 or for any other purpose, it is only 100 necessary for the operator to hold the parts with the lower end of the screw 46 bearing on the arm 35 until the eye bolt is again clamped.

The slide 24 is provided with a rigid arm 105 48 through which a screw 49 passes, a binding nut 50 being employed to hold the screw 49 in adjusted position to serve as a stop to limit downward movement of the arm 35.

In the embodiment of the invention illustrated in Figs. 4, 5 and 6 the parts having the same reference characters as employed in Fig. 1 are the same or substantially the same as those parts.

As shown in Figs. 4 and 5 the shank 39 115 of the cutter rest 40, instead of being circular in cross-section is ovoid, and so fits the V-shaped groove in arm 51 that said shank can not be rotated in said arm. Rotative adjustment in order to vary the angular position of 120 the cutter rest 40 is effected by providing for rotative adjustment of the arm 51 relatively to the bar 34 which, of course, is pivotally supported in the same manner as the similarly numbered member in Fig. 1. To 125 this end, the base 52 of the arm 51 is formed with a sleeve 53 rotatively mounted in an opening in the bar 34 and held therein by means of a screw 54 (Figs. 4 and 6) passing through a washer 55 into said sleeve 53. A 130

portion of the edge of base 52 is formed or provided with teeth 56 engaged by a worm screw 57 mounted in lugs 58 of the bar 34. By rotating the worm 57 the arm 51 and consequently the cutter table or rest 40 and its pin 41 can be easily adjusted to vary the angular position of the pin 41 relatively to the plane of the operating face of the grinder 15. Owing to the fact that the shank 39 (Fig. 4) can not be rotated relatively to arm 51, the eye bolt 42 can be loosened and clamped again whenever the entire pivoted arm is to be lengthened or shortened without disturbing the angular adjustment of the cutter support 40, 41. As indicated in Fig. 6 I may provide the bar 34 with scale marks 59 to coöperate with an indicating mark 60 carried by the base 52 of the member 51.

20 Whether the invention is embodied in a device of the specific character indicated in Fig. 1 or Fig. 4, the pivoted member 34, 33 and the longitudinally extensible arm for the cutter carried thereby is limited in its upward movement under the influence of spring 36 by a lug 61 projecting from one of the ears 31 into the path of a portion of an ear 33 below the pivot 32.

As indicated in Fig. 3 the bar 34 is provided with a lug 62 against one side of which the end of spring 36 bears. This is to prevent lateral play of the bar 34 and its ears 33 which would interfere with oscillating movement of the cutter carrying arm in an accurate plane. By having the end of the spring 36 deflected to bear against one side of the lug 62, said spring serves the double purpose of not only urging the entire extensible arm upwardly on the pivot 32, but also urges one of the ears 33 against one of the ears 31 as shown at the right in Fig. 3 so as to guide the cutter carrying arm in a predetermined oscillatory plane.

It will now be understood that in the operation of either of the devices illustrated the cutter may be oscillated through an arc intersecting the periphery of the grinding member, with the result that the cutter may be brought into and removed from engagement with the grinding member by a continuous sweeping movement of the cutter supporting arm, and when any longitudinal adjustment of the arm is desired, the same can be effected without liability of disturbing the proper angular position of the end of the arm which carries the cutter.

As fully explained in my former application No. 162,758, each tooth of the cutter can be brought into position and subjected to the action of a grinding wheel by simply rotating the cutter on the pin 41 when in a position away from contact with the grinding wheel, and by then simply depressing the extensible arm against the action of spring 36, holding the cutter at the same time with

the face of the tooth to be ground bearing against and passing over the surface of the grinding wheel.

Referring to Fig. 1, the bracket 17 is provided with a threaded hole in front of the slot 18, and a screw 63 passes through said hole to contact with an abutment or lug 64 rising from the frame ledge 21. Preferably, there are two lugs 64, one in front of and the other behind the screw 20, said lugs having a width corresponding with the width of the slot 18. Obviously, the two lugs 64 might be merged into a single rib fitting the slot 18, with the screw 20 rising from the rib. As indicated in Fig. 1 the frame ledge 21 is wide and formed with duplicate sets of lugs 64 and screws, to enable right and left hand attachments to be employed. Many machines of this character have a grinding member at each end of the shaft 14, the illustration showing but one for lack of space. Assuming, however, that such a machine has a second grinder carried by that portion of the shaft which is broken away, then an attachment similar to the one illustrated but having the outer end of the bracket 17 curved to the right instead of to the left, would, when needed, be mounted on the part of the ledge 21 which is shown as unoccupied.

95 The screw 63 is employed to render certain the correct replacement of the attachment after removal. Assuming that the attachment has been correctly set as indicated in Fig. 1 and it is to be temporarily removed, the operator simply turns the screw 63 so that its inner end bears against the front face of the lug 64 and then loosens the clamp screw 19 and removes the attachment which may then, at any time so long as the screw 63 has not been disturbed, return the attachment to the exact position relatively to the grinder which it formerly occupied.

100 While I have herein shown and described two preferred embodiments of my invention, it is to be understood that I do not desire to be limited to either of the exact arrangements shown.

110 Having described my invention, what I claim as new and desire to secure by Letters Patent of the United States is:

1. In a machine for grinding rotary cutters, an arm, a cutter support angularly and longitudinally adjustable on the arm, means for retaining the cutter support in its position of longitudinal adjustment and means for preventing disturbance of the angular adjustment when altering the longitudinal adjustment.

120 2. In a machine for grinding rotary cutters, an arm, a cutter support angularly and longitudinally adjustable on the arm, means for retaining the cutter support in its position of longitudinal adjustment, means for determining the degree of angular adjust- 130

ment, and means for retaining that adjustment when altering the longitudinal adjustment.

3. In a machine for grinding rotary cutters, an arm, a cutter support angularly and longitudinally adjustable on the arm, means for determining the degree of angular adjustment; and means including a screw for effecting and retaining that adjustment when 10 altering the longitudinal adjustment.

4. A machine of the character described, comprising a grinding wheel, a pivoted member mounted for movement on an axis substantially parallel to the axis of the 15 grinding wheel, a cutter support angularly and longitudinally adjustable on the pivoted member, and means for preventing disturbance of the angular adjustment when altering the longitudinal adjustment.

20 5. A machine of the character described, comprising a grinding wheel, a pivotally supported extensible arm having a cutter support at its free end, and means for insuring retention of the predetermined angular 25 position of the cutter support relatively to the grinding wheel when the extensible arm is varied in length.

6. In a machine for grinding rotary cutters, a grinding wheel, a support, an arm 30 pivotally mounted upon said support for movement about an axis substantially parallel to the axis of the grinding wheel, a cutter supporting table adjustably carried by said arm to vary the angle between the plane 35 of said table and the plane of oscillation, and means both for effecting and maintaining a fine angular adjustment of the table.

7. In a machine for grinding rotary cutters, a grinding wheel, a support, an arm 40 pivotally mounted upon said support for movement about an axis substantially parallel to the axis of the grinding wheel, a cutter supporting table adjustably carried by said arm to vary the angle between the 45 plane of said table and the plane of oscillation, a screw to turn the table angularly on the arm, and means for adjusting said support in a direction substantially parallel with the axis of rotation of the grinding 50 wheel, said adjusting means including a rack and pinion.

8. In a machine for grinding rotary cutters, a grinding wheel, a swinging arm, an angularly adjustable and longitudinally 55 slidable cutter-carrying member mounted to rotate and slide upon said swinging arm, and means for preventing disturbance of the angular adjustment when altering the longitudinal adjustment.

60 9. In a machine for grinding rotary cutters, a grinding wheel, a bracket adjustably mounted relatively to said wheel, a cutter arm pivotally supported by said bracket, resilient means for actuating said arm in one 65 direction, a stop for opposing the action of

said resilient means, and an adjustable stop for limiting the movement of said arm in the direction which is opposed by said resilient means.

10. In a machine for grinding rotary cutters, a pivoted yieldingly-supported longitudinally-grooved arm, a cutter support having a shank engaging the groove of the arm, a clamp for binding said shank in position, and adjustable means for determining 75 the angular position of the cutter support when the clamp is loosened.

11. In a machine for grinding rotary cutters, a pivoted yieldingly-supported member, an arm rotatably connected therewith, 80 means for rotatably adjusting said arm, a cutter support having a shank engaged with said arm, and means for clamping said shank and arm together.

12. In a machine for grinding rotary cutters, a pivoted yieldingly-supported member, an arm rotatably connected therewith, said arm having a toothed portion, a worm screw carried by said member and engaging its teeth to rotatively adjust the arm, a cutter support having a shank slidably connected with the arm, and means for clamping 90 said shank and arm together.

13. In a machine for grinding rotary cutters, a pivoted yieldingly-supported member, a longitudinally-grooved arm rotatably connected with said member the axis of rotation being in line with the groove of the arm, a cutter support having a shank engaging the groove of the arm, a clamp for 100 binding said shank in position, and means for rotatively adjusting said arm and the cutter support clamped thereto.

14. In a machine for grinding rotary cutters, a pivoted yieldingly-supported longitudinally-grooved arm, a cutter support having a shank engaging the groove of the arm, a clamp for binding said shank in position, and a screw carried by said shank to coact 105 with a portion of the arm to control rotative position of the shank in the groove of the arm.

15. The combination with a grinding machine having a ledge, of a work supporting attachment normally projecting beyond the 115 ledge, means for releasing the attachment from the ledge to provide more space around the machine, and means for insuring accurate replacement of the attachment after it has been removed from the machine. 120

16. A grinding machine having a removable work-supporting attachment, the frame of the machine and the attachment having co-operating abutting members, one of which is adjustable, to determine the position of 125 the attachment relatively to the grinding element of the machine.

17. A work-supporting attachment for a grinding machine, said attachment having a base portion provided with a slot to en- 130

gage a coöperating fixed member of the machine, and a screw mounted in said base member and constructed and arranged to engage a fixed abutment of the machine.

5 18. A grinding machine having its frame provided with means for attaching a work-support thereto, said means including a clamp and an abutment, and a work-supporting attachment having a base portion

provided with a slot to engage the sides of 10 said abutment and a screw constructed and arranged to coöperate with said abutment to determine the position of the attachment relatively to the grinding machine.

In testimony whereof I have signed my 15 name to this specification.

HENRY M. LOOMER.
